UNITED STATES PATENT OFFICE

139,558

DESIGN FOR A CUTTING ATTACHMENT FOR PENCILS OR THE LIKE

Helen Vuksich, Duluth, Minn.

Application August 21, 1944, Serial No. 114,953

Term of patent 7 years

(Cl. D74—1)

To all whom it may concern:

Be it known that I, Helen Vuksich, a citizen of the United States, residing at Duluth, in the county of St. Louis and State of Minnesota, have invented a new, original, and ornamental Design for a Cutting Attachment for Pencils or the Like, of which the following is a specification, reference being had to the accompanying drawing, forming part thereof.

Fig. 1 is a side elevational view, showing my new design,

Fig. 2 is an edge elevational view of Fig. 1, and

Fig. 3 is a top plan view of same.

I claim:

The ornamental design for a cutting attachment for pencils or the like, as shown.

HELEN VUKSICH.
